LIVESTOCK WATERING TANK HEATER

Jack P. Thomas, P.O. Box 1, Dighton, Kans.

Filed Jan. 11, 1965, Ser. No. 83,393

Term of patent 3½ years

(Cl. D81—2)

FIGURE 1 is a front elevation of the livestock watering tank heater, showing my new design;

FIGURE 2 is a left-side elevation thereof; and

FIGURE 3 is a right-side elevation.

The rear elevation is a mirror-image of the front elevation. The bottom is plain except for the four legs at the corners.

I claim:

The ornamental design for a livestock watering tank heater, as shown and described.
